UNITED STATES PATENT OFFICE.

JAMES H. BLESSING, OF ALBANY, NEW YORK.

APPARATUS FOR ELIMINATING LUBRICANT FROM EXHAUST-STEAM.

SPECIFICATION forming part of Letters Patent No. 514,440, dated February 13, 1894.

Application filed July 12, 1893. Serial No. 480,230. (No model.)

To all whom it may concern:

Be it known that I, JAMES H. BLESSING, of the city and county of Albany, in the State of New York, have invented new and useful 5 Improvements in Apparatus for Eliminating Lubricant from Exhaust-Steam, of which the following is a specification.

This invention is designed for use in vertical exhaust-pipes, and it consists of several 10 communicating chambers arranged in a vertical series and having a steam-passage leading from the top of each chamber into the next above it, each chamber having a dome-shaped baffle-plate arranged over said steam- 15 passage for the purpose of forcing the steam to discharge laterally into the chamber, and each chamber having a series of pendent retard-ing-plates of a trough-like form arranged to receive the impact of the escaping steam 20 containing the lubricant which, having greater affinity for the metal of said plates than for the steam, will be deposited on said retard-ing-plates and drip therefrom into the lower 25 part of the chamber, as hereinafter more fully set forth.

In the accompanying drawings, which are herein referred to and form part of this specification, Figure 1 is a vertical section of my apparatus of three communicating chambers; 30 said section being taken at the line X X on Fig. 2. Fig. 2 is a plan view of said apparatus; and Fig. 3 is a horizontal section at the line Y Y on Fig. 1.

As represented in the drawings, A designates a tubular body-piece which forms the shell for the different chambers of my apparatus, the number of said body-pieces corresponding to the number of chambers required in the apparatus; each of said body-pieces has 35 a passage, B, which forms a communication between the upper and lower ends of the chamber; leading laterally from the passage B—at a height at which it is designed to maintain the level of the condensed water in the 40 chamber to which it pertains—there is a waste-water pipe, C, whose passage is controlled by a stop-valve, D, or other suitable appliance, which must remain open during the time the lubricant is being collected in 45 the corresponding chamber. At the opposite side of said body-piece there is an outlet-lubricant pipe, E, leading laterally from the

chamber, and the bore of said pipe is preferably arranged to come a little below the bore of the pipe C. An oil-gage, F, is arranged at 55 the outer end of the pipe E and is provided with transparent sides, G, to afford visible evidence of the level attained by the lubricant and water collected in the apparatus. A stop-cock, H, is fixed in the lower part of 60 said gage for the purpose of drawing off the lubricant, but, during the latter operation, the waste-water valve D must remain closed to permit the water condensed from the steam to accumulate in the chamber and thereby 65 raise the lubricant, that floats on the surface of the water, to a level where it can pass into the gage F, wherefrom it can be drawn through the cock H.

I designates the bottom-plate of my apparatus which is provided with a neck, J, that is fitted to connect with an exhaust-pipe, said neck being formed centrally on the lower side of said plate, and a collar, K, is formed on the upper side of said plate and so arranged 75 that the bore of said collar will correspond with the opening through the neck J, thereby forming a continuation of the exhaust-pipe into the chamber. A groove is formed on the upper side of the plate I to receive a packing, 80 L, which forms a steam-tight joint for the lower end of the body-piece A that constitutes the outer wall of the lower chamber.

M designates the division-plates which separate the chambers from each other; each of 85 said division-plates is provided with a centrally-located collar, N, which is formed on its upperside and surrounds a passage, O, through which the exhaust steam, from the underlying chamber, will pass to enter the successive 90 chambers. Pendent from each division-plate M is a dome-shaped baffle-plate, P, arranged to cut off a direct line of communication between the exhaust passages of the several plates; said baffle-plates are suspended from 95 the division-plates by means of hangers, Q, which retain said baffle plates in position but afford ample space for the exhaust steam in its passage from one chamber into the next 100 succeeding chamber. Each division-plate has, in its upper and lower faces, a groove for containing a packing, R, to form a steam-tight joint with a corresponding end of the body-piece A that is appropriated to the par-

ticular chamber to which the division-plate forms a separation.

5 S designates the cap-plate which forms the top of my apparatus; said cap-plate has—on its upper face—a neck, T, which is fitted to receive a continuation of the exhaust-pipe. The lower face of said cap-plate has a baffle-plate, P', pendent from it, and a groove formed on the lower side of said cap-plate contains a 10 packing, R', which forms a steam-tight joint at that point.

15 U designates the trough-shaped retarding-plates which are pendent from each division-plate M and from the cap-plate S; said retarding-plates are usually arranged in concentric rows—as shown in Fig. 3—and in such manner that a space between the edges of two adjacent plates of the same row will be opposite to the concave face of a retarding-plate of the adjacent row, so that the steam which passes through such a space will be 20 caught by the retarding-plate which covers said space.

25 V designates a series of screw-bolts which pass through lugs, W, formed on the plates I, M, and S, for the purpose of binding the several parts of my apparatus securely together.

30 It should be understood that the collars K and N must be formed to extend above the level of the pipes C in order to form a suitable reservoir for containing the eliminated lubricant in each chamber of my apparatus, and it should also be understood that the several waste-water pipes C—leading from the 35 stop-valves D—can be connected to a single waste-water pipe that will conduct the waste-water from all the chambers of the apparatus.

40 The operation of my apparatus is as follows: Said apparatus being secured in a vertical exhaust-pipe of a steam-engine, the steam will pass upwardly through the collar K in the lower chamber of the apparatus and, by striking the lower baffle-plate P, will escape laterally from under the latter to impinge against the retarding-plates U in the lower chamber; the lubricant—held in suspension by the steam—having a greater affinity for the metal of the retarding-plates 45 than for the steam, is lodged on the concave surface of said retarding-plates from whence it trickles down into the bottom part of said chamber where it will float on the surface of the water produced by the condensation of a portion of the steam which has entered the 55 chamber; the uncondensed portion of the steam will then pass upward through the passage O of the lower division-plate M, striking the second baffle-plate P and, being deflected 60 against the retarding-plates U in the second chamber to undergo the operation just described, whereby a further quantity of lubricant is eliminated from the steam, and this operation is repeated in the successive chambers until all the lubricant is eliminated from the 65 exhaust-steam, after which the latter will escape through an exhaust-pipe attached to

the neck T. When the oil-gage F, of either chamber of the apparatus, indicates that a sufficient quantity of lubricant has been collected in that chamber, the corresponding 70 stop-valve D should be closed to prevent the outflow of the waste-water from said chamber being continued; the closing of said stop-valve causes the water to rise in the chamber.

75 Simultaneously with the closing of said stop-valve the stop-cock H should be opened and, as the water rises in the chamber, the lubricant will be carried into the gage F from whence it will escape, through said stop-cock, 80 and be caught in a suitable receptacle. This operation can be continued until the lubricant is drawn from the several chambers, or,

85 in case any gage F does not show a sufficient quantity of lubricant in either of the chambers, only the chambers containing a required quantity of lubricant need to be drawn off.

90 When a profuse discharge of steam from either of the stop-cocks H indicates that the lubricant has all been discharged from the corresponding chamber of the apparatus, said stop-cock should be closed and the corresponding stop-valve D opened, to restore that chamber to a condition for eliminating the lubricant from the exhaust-steam. The wa-

95 ter in the lower part of each chamber forms a water-seal that will prevent the lubricant from being carried up into the passage B—the pressure on the surface of the water being equalized in the chamber and its pas-

100 sage B—and thence out of the waste-water pipe C pertaining to that particular chamber. The exhaust-steam on entering the lower chamber of my apparatus undergoes an ex-

105 pansion due to the increased area of the chamber, but the next impulse of the exhaust ac-

110 celerates its passage into the succeeding chamber, where it undergoes a similar expansion and acceleration, and this action is continued until the steam has passed through the sev-

115 eral chambers to finally escape from the ap-

paratus; these several retardations of the pas-

120 sage of the exhaust-steam operate to effect a more perfect separation of the lubricant from the steam.

125 It is manifest that this apparatus cannot be used in a horizontal position.

130 What I claim as my invention, and desire to secure by Letters Patent, is—

1. An apparatus for eliminating lubricant 135 from steam consisting of a series of vertically-arranged chambers which communicate with each other through an opening formed in the division-plates; each of said openings being surrounded by a collar to form a receptacle 140 for receiving the lubricant and water at the bottom of each chamber, each of the latter containing a passage which leads from the steam-space of the chamber to a level below the surface of the water; whereby a water-

145 seal will be formed at the lower end of each passage, a waste-water pipe leading from each 150 of said passages and provided with a stop-

155 valve, a baffle-plate interposed between the

successive steam-passages between said chambers, and a series of pendent trough-like retarding-plates contained in each chamber and arranged in such manner that an open space 5 between adjacent plates will be opposite a plate of the succeeding row of said plates, as and for the purpose specified.

2. The combination of a body-piece provided with a passage, B, which—by forming a separate communication between the upper and lower ends of the chamber formed by said body-piece—equalizes the pressure on the surface of the liquids contained in said chamber and passage, a waste-water pipe, C, leading 15 from said passage at the water-level of the apparatus, a lubricant-outlet, E, leading from said chamber near the water-level of the apparatus, a bottom-plate provided with an exhaust-passage surrounded by a collar which—

in conjunction with the body-piece—forms a 20 water-receptacle in said chamber, a top-plate provided with an exhaust-passage corresponding to the like passage of the bottom-plate, a dome-shaped baffle-plate pendent from said top-plate directly under the ex- 25 haust-passage of the latter and arranged to form a lateral opening with approximately parallel upper and lower edges between itself and the upper end of the collar of the bottom-plate, and a series of trough-like retarding- 30 plates pendent from said top-plate and arranged in circular rows around said baffle-plate, as and for the purpose specified.
